UNITED STATES PATENT OFFICE.

JOHN WILLIAM CALDWELL, OF TORONTO, ONTARIO, CANADA.

BIT FOR BORING SQUARE AND ANGULAR-SHAPED HOLES.

1,066,708.

Specification of Letters Patent.

Patented July 8, 1913.

Application filed June 24, 1908, Serial No. 440,179. Renewed December 2, 1912. Serial No. 734,629.

To all whom it may concern:

Be it known that I, JOHN WILLIAM CALDWELL, a subject of the King of Great Britain, and resident of the city of Toronto, in the county of York, in the Province of Ontario, in the Dominion of Canada, have invented certain new and useful Improvements in Bits for Boring Square and Angular-Shaped Holes, of which the following 5 is a specification.

10 The invention relates to improvements in bits for boring square or angular holes, as described in the following specification and illustrated in the accompanying drawings 15 that form part of the same.

15 The invention consists essentially in the novel construction and arrangement of parts whereby the chips cut are carried freely through a hollow broach by a rotating spiral 20 bit formed in cross section with parallel straight faces of considerably greater width than half the diameter of the bit.

25 The objects of the invention are to devise a bit for cutting square or angular shaped holes quickly and perfectly and prevent choking and to provide a tool for said purpose of cheap, simple and durable construction.

30 In the drawings Figure 1 is a side view of the bit proper showing the broach mounted thereon and turned cornerwise. Fig. 2 is a side view of the bit proper showing the broach from another point of view. Fig. 3 is a side view of the bit proper and showing the broach in section and a cross section 35 of the spiral broken away intermediate of its length. Fig. 4 is an end view of the bit proper and the broach. Fig. 5 is a cross section on the line A B in Fig. 1. Fig. 6 is an end view of a bit for cutting a dovetail hole. Fig. 7 is an end view of a bit 40 for cutting a hexagonal hole. Fig. 8 is an end view of a bit for cutting an octagonal hole.

45 Like numerals of reference indicate corresponding parts in each figure.

Referring to the drawings 1 is the rotary member or bit proper formed of the spiral 50 2 having parallel straight faces 3 and lateral flanges 4 at the outer edges forming a pair of spiral channels of greater width than half the diameter of the hole cut thereby. The bit 1 is flared outwardly at the bottom end and the lower end of the spiral is sharpened between the flanges 4 to form the horizontal cutters 5. The flanges 4 extend be-

yond the horizontal cutting edges 5 and are sharpened to form side cutters.

60 6 is a lead screw having a double thread forming a continuation of the horizontal cutters 5, said threads being undercut on the inner surfaces of the thread presenting downwardly projecting cutting edges, said threads terminating in a pair of downwardly extending chisel points 7 extending 65 beyond the tapered point of the central core 8. The top 9 of the bit is square to fit into the separable shank 10.

11 is an angular shaped broach of exactly the same diameter as the cutting end of the 70 bit proper 1 having a central circular orifice 12 extending therethrough. The orifice 12 has a long bevel at the lower end corresponding with the outward flare of the bit 1 and terminates at each corner 13 in an 75 extending chisel point or guillotine edge. The side cutters of the bit 1, in rotation extend flush with the outer flat faces of the broach 11 so that it cuts a circular hole of exactly the same diameter as the broach. It 80 will therefore be seen that the broach has only to cut away the fillets in said circular hole to form the square or angular hole.

14 is a loose washer encircling the bit 85 above the broach 11.

15 is a collar encircling the bit 1 and secured thereto by the set screw 16, said collar being adjusted to hold the washer 14 against the upper end of the broach 11 and to hold the tapered inner wall of said broach closely 90 to the flared portion of the bit 1. The shank 10 and bit 1 are rigidly secured together by a suitable pin after the broach 11 and washer and holding collar are mounted thereon. The channels formed in the bit 1 95 are, in the reduced portion of said bit, considerably wider than half the diameter of the cutting end, so that there is sufficient space for the chips cut by the rotative bit and the broach to ascend the spiral without 100 choking, therefore the hole may be finished without removing the bit.

105 In operation the lead screw 6 is started into the wood and from its peculiar formation draws the bit thereafter without extra pressure being brought to bear on the tool, the side cutters are thus brought into play and a round hole cut. The broach 11 is carried with the rotating member and held in its proper position until the sharpened 110 points enter the wood and chisel out the fillets.

Three modifications of the shape of the broach are shown in Figs. 6, 7 and 8, but it must be understood that many changes may be made in the form thereof so long as the 5 stationary guillotine edges for cutting away the fillets are associated with a rotating cutting member.

The form of bit herein shown and described is adapted for use in a hand brace, 10 or it may be used with equal facility in wood working machines of various kinds, and may also be used for boring mortises or other long shapes of holes by modifying the shape of the broach and using two or more rotat- 15 ing members.

The present invention relates particularly to the adaptation of the auger bit described in my co-pending application 440,177 to a bit for boring square and angular shaped 20 holes.

Hitherto it has not been possible to bore square or angular shaped holes successfully on account of the clogging and choking of the rotating bit. In the present invention 25 however, the spiral of the rotating member is so formed that there is ample clearance for the chips and a successfully operating bit is produced.

What I claim as my invention is:—

30 1. An auger bit, comprising, a spiral body portion having a cross sectional shape showing parallel straight faces, said straight faces presenting channels of greater width than half the diameter of the bit, and a hollow 35 broach surrounding said bit above the cutting end and having angularly arranged

sides and chisel edges at the lower end thereof.

2. An auger bit, comprising, a spiral body portion having a cross sectional shape showing parallel straight faces, said straight faces presenting channels of greater width than half the diameter of the bit, said bit terminating in cutting edges to each side of the central lead screw and having side 40 flanges forming side cutters at the bottom end, and a hollow broach surrounding said bit above the cutting end and having angularly arranged sides and chisel edges at the lower end thereof. 45

50 3. An auger bit, comprising, a spiral body portion having a cross sectional shape showing parallel straight faces, said straight faces presenting channels of greater width than half the diameter of the bit, the spiral 55 of said bit increasing in diameter toward its lower end and forming a gradual flare to said bit, said bit having side flanges forming side cutters at the bottom end, and a hollow broach surrounding said bit and hav- 60 ing angularly arranged sides, said sides having the inner wall flaring outwardly and forming chisel edges at the lower end thereof.

Signed at the city of Toronto in the 65 county of York in the Province of Ontario, in the Dominion of Canada, this 16th day of June 1908.

JOHN WILLIAM CALDWELL.
